BEVERAGE DEFOAMING DEVICE

Roland E. Renard, Los Gatos, Calif., assignor to
Pacific Can Company, San Francisco, Calif., a
corporation of Nevada

Application September 15, 1950, Serial No. 185,067

6 Claims. (Cl. 226—69)

1

This invention relates to new and useful improvements in beverage defoaming devices, and more particularly to the removal of large bubbles from the head space of containers of foaming liquids prior to sealing and the substitution therefor of small bubbles of gas induced by treatment of the liquid in the can. The invention is particularly useful in the treatment of canned beer, ale, and the like, in that the large, air-filled bubbles normally existing in the head space of the can immediately after being filled are burst and the head space is filled with small, creamy bubbles of CO₂ induced by heating and mildly agitating the beer near the surface to cause bubbles of CO₂ in the liquid to rise. Reference is made to the co-pending application of Earl E. Jeremiah, Serial No. 103,344, filed July 7, 1949.

The presence of air inside cans of beer, ale and similar products is extremely undesirable because of the deleterious effect of the oxygen in the air upon the taste and color of the beverage upon aging. Air may reach the inside of the can from either of two sources: First, the air may be entrained in the liquid during filling of the can, the air usually being associated with CO₂ gas, and rising to the top of the can in large bubbles of uneven size. Second, inasmuch as the can is ordinarily not filled to the top of the flange—the unfilled portion being commonly termed "head space"—air may fill this space before the cover is applied and be sealed in the can. The present invention is an improved apparatus and method for eliminating air from both sources.

Superheated steam is used to accomplish the above-described purposes, which is advantageous in that steam is readily available in a brewery with little or no cost. Further, steam cannot have a deleterious effect upon the beer other than a slight dilution, even if a particular can should come to rest under the apparatus for a protracted period due to stoppage of the filling line. Further, there is no danger of noxious or toxic gases being trapped in the cans, as may occur if an open flame of gas is used to burn off air bubbles and should accidentally become extinguished; nor is the color of the beer affected, as may be the case with devices which burn off the foam.

One of the features of the present invention is the fact that the apparatus used to accomplish the invention is compact and thin by reason of the unique construction thereof and this permits the installation of the apparatus in existing brewery filling lines without material alteration thereof.

Another feature of the invention is the equal distribution of steam which results from the apparatus hereinafter described. The equal distribution of steam permits accomplishment of bursting of the air bubbles in a minimum of time and further permits use of thin, compact apparatus.

2

The construction of the apparatus further provides for the formation both of a fog of steam and a jet of steam, each independent of the other and each independently controllable. All of the foregoing features and advantages of the construction of the apparatus and method are hereinafter described in greater detail.

In addition, means is provided to avoid condensation or reduction in the temperature of the steam by shielding the apparatus from cold liquids such as dripping beer which might contact the device.

With the above and other objects, features and advantages in view, the invention consists in the matters hereinafter set forth and more particularly pointed out in the appended claims, reference being had therein to the accompanying drawings, in which:

Fig. 1 is an exploded view of the parts comprising the apparatus;

Fig. 2 is a bottom plan view of the body member;

Fig. 3 is a longitudinal vertical section of the device, the line on which said section is taken being indicated by line 3—3 of Fig. 2;

Fig. 4 is a section similar to Fig. 3 as indicated by line 4—4 of Fig. 2;

Fig. 5 is also a section similar to Fig. 3 as indicated by line 5—5 of Fig. 2;

Fig. 6 is a diagram of the steam circuit employed in the present invention.

In carrying out the present invention, open top cans 10 are first filled with beer, ale or similar foaming liquid in a conventional filler. Because of the high speed at which such fillers commonly operate, it is practically impossible to avoid the presence of a large percentage of air within the large, uneven bubbles occurring in the head space of the can and the interstices of such bubbles.

If allowed to remain in the can, after sealing the oxygen in the entrapped air will adversely affect the color and taste of the beer. The present invention is installed in the line between the filler and the can seamer so as to condition the beer prior to sealing the cover on the can. The conditioner not only removes the large air-containing bubbles, but also fills the head space of the can with small, creamy bubbles of CO₂ with little or no air therein or in the interstices. Thus when the cover has been sealed on the can, little or no air is entrained.

The large bubbles of air are burst by passing through a heated fog or atmosphere of, preferably, superheated steam which elevates the temperature of the gas in the bubbles until they burst. A jet of superheated steam is forced slightly below the surface of the liquid to heat and agitate the beer so as to cause small, creamy bubbles to rise above the liquid surface and fill the head space of the can completely. A single apparatus may be used to perform both steps and a single source of steam employed. Thereafter the can,

the head space still filled with creamy bubbles displacing all air with a slight crown above the level of the flange, is passed to the seamer and the cover applied.

Steam, preferably superheated, used in conjunction with the apparatus hereinafter described, may be produced in any of various ways, as by the use of a thermostatically-controlled electric heater in the steam line leading from the boiler to the instant device. The line of superheated steam is divided into two branches, one branch leading to the portion of the device which creates the fog of steam and the other leading to the jet of steam which causes foam to rise and fill the head space of the cans. Suitable control valves may be installed in each branch line, each independently controlling the amount of steam in each branch. A preferred means for supplying steam under pressure is illustrated diagrammatically in Fig. 6. Steam under approximately 100 p. s. i. is introduced to heating chamber 51, said chamber being cylindrical and provided with a thermostatically-controlled electric heating element 52 which holds the steam passing through chamber 51 at a desired temperature, preferably 300° F. A strainer 53 is provided in the line to remove undesirable material.

The steam thence passes to a 3-way valve 54. This valve is preferably solenoid-controlled and connected into the motor control circuit for the seamer (not shown) so that when the seamer is stopped the flow of steam will be diverted to trap 56 and will not pass through the conditioner system. It is important that the steam be diverted else the can stopped immediately under the conditioner will be spoiled because an excessive amount of CO₂ will escape therefrom and the beer will become flat, which produces an unfavorable customer reaction. However, so that the conditioner is not cooled excessively during temporary shutdowns, which would result in condensation of steam and consequent dilution of the beer, a by-pass is established through pipe 57 around valve 54, the amount of flow through said by-pass being regulated by valve 58 to accomplish the objects of the preceding sentence.

From the 3-way valve 54 the steam branches into two pipes 61 and 62, having regulating valves 63 and 64, respectively, and leading to fittings 16 and 31, as hereinafter described.

The device which is the subject of the invention comprises three members, a bottommost perforate screen 11, a chamber-forming body 12, and an uppermost drip pan 13. Drip pan 13 is elevated above body 12 to intercept any beer or other cold liquid which might otherwise contact the body and chill the superheated steam. Screen 11 and body 12 fit closely together, forming a seal, and since the body is formed with a plurality of channels and passageways routed out of the surface adjacent the screen, the two members form a chest for the superheated steam. A separate passageway is likewise formed for the jet of steam, as hereinafter described.

Steam employed to produce the fog or atmosphere of steam is introduced through a pipe fitting 16 fixed to the surface of the body 12 opposite screen member 11. Body 12 is drilled out as indicated by numeral 17 at a diameter substantially equal to the inner dimension of fitting 16 in order to form a port for the ingress of steam. Port 17 communicates through lateral passageway 18 with longitudinally extending channel 19 which is located proximate one longitudinally

extending edge of body 12 and extends practically the entire length thereof, being routed into the surface of said body 12. Leading inwardly from said channel 19 is a plurality of lateral grooves 21 disposed at right angles to said channel, likewise routed into the surface of said body, and spaced apart approximately equal distances. Said grooves 21 terminate in substantially rectangular cavity 22 recessed into the surface of said body, said cavity occupying substantially one-half of the bottom surface area of said body and extending along practically the entire length of said body along the edge thereof opposite channel 19.

Sealed against body 12 by a plurality of screws 23 is screen member 11, the bottom and top surfaces of which are planar. It will be noted that screen 11 is perforated in a plurality of small holes 26 in a zone immediately below cavity 22. By reason of screen member 11 being sealed against body member 12, the flow of steam is confined within the passageways defined by channel 19, grooves 21, and cavity 22. The arrangement of said channel 19 and grooves 21 is such as to insure even distribution of steam within cavity 22 so that the various perforations 26 in screen 11 receive and discharge substantially equal amounts of steam. Thus an even, homogeneous fog of steam is produced through which cans 10 pass.

As has been stated, in addition to the fog created by steam emitted from perforations 26, a jet of steam is also produced which penetrates the large bubbles on the surface of the liquid in cans 10 and raises a creamy foam which fills the head space. Such steam is introduced into the chest through fitting 31 on the upper surface of body 12, there being a communicating hole 32 in the body member providing an entry port. Groove 33 extends laterally from said port 32 in the direction of cavity 22, there being a raised zone 34 in cavity 22 to provide stock into which said groove 33 may be cut and thus to create a passageway for steam which is separated from the steam entering through port 17. Screen member 11 is imperforate in the line immediately below said groove 34 except that a single hole 36 is formed adjacent the end of said groove, said hole being of slightly greater diameter than perforations 26. The location of hole 36 is such as to be above the line of the centers of cans 10 being treated.

Drip pan 13 is attached to the upper side of body member 12 by screws 41, said drip pan being dimensioned so that it does not intersect fittings 16 and 33. The purpose of the drip pan is to prevent cold liquid such as dripping beer from contacting body member 12, and thus to prevent condensation of the steam within cavity 22. Thus said pan is connected to body 12 along its two longitudinal edges 42 and 43 but is elevated from said body intermediate said edges as indicated by reference numeral 44. Along the lateral edges of pan 13 are upstanding sides 46 which prevent liquid from running over said edges. The upper surface of pan 13 is thus concave and also elevated above body 12 except at edges 42 and 43. Thus pan 13 traps liquids which might otherwise drip onto body 12 and chill same.

In operation, cans 10 are passed from the filler so that their top flanges pass immediately below the under-surface of screen 11 and the path of travel of the cans extends substantially the length of the perforated portion of said screen. Steam entering through fitting 16 is distributed

substantially uniformly throughout cavity 22 and thus is emitted through perforations 26 in a continuous, homogeneous fog. Said fog heats and expands the bubbles of foam on the surface of the beer so that they burst. Simultaneously, steam entering through fitting 31 is emitted from hole 36 in form of a jet of mild pressure, which penetrates the foam on the liquid surface approximately $\frac{1}{2}$ inch below said liquid surface, thereby agitating the liquid and partially warming same, thereby causing the CO₂ in the liquid to rise in the form of a creamy head which fills the head space of the can and substantially displaces all air. Said creamy head endures until after the cover has been sealed on the can; thus the sealed container has a minimum of deleterious oxygen. The relative emission of steam through perforations 26 and hole 36 may be controlled by means of valves 63 and 64 as may the pressure of the steam to the two branches. Thereby the two functions of the apparatus and method are accomplished without using an excessive amount of steam which might dilute or cause flatness of the beer.

It will be understood that whereas a preferred embodiment of the invention has been described and illustrated, changes may be made therein without departing from the spirit of the invention and the scope of the appended claims. For example, containers other than metal cans might be used with the conditioner and liquids other than beer and ale treated.

What is claimed is:

1. In a conditioner for open containers of foaming liquids initially having large bubbles, a chest positioned above the path of travel of said containers, said chest having a screen member perforated in a zone beneath which said containers pass, a body member sealed against said screen member, said body member being formed with a cavity in its surface facing said screen member and overlying the perforate zone of said screen member, a channel cut into said body member and a plurality of grooves leading from said channel to said cavity, said cavity, said grooves and said channel forming with said screen member passageways for steam, said screen member having a hole in a zone beneath which said containers pass, an additional groove in said body member providing communication for discharge of steam through said hole, first means for providing steam to said channel and second means for providing steam to said additional groove.

2. A conditioner as defined in claim 1 which further includes a drip pan elevated above said body member and being concave upward to catch liquid and prevent contact of said liquid with said body member.

3. In a conditioner for open containers of foaming liquids initially having large bubbles, a chest positioned above the path of travel of said containers, said chest having a screen member perforated in a zone beneath which said containers pass, a body member sealed against said screen member, said body member being formed with a cavity in its surface facing said screen member and overlying the perforate zone of said screen member, a channel in said surface of said body member extending along one longitudinal edge of said body member, a plurality of spaced, lateral grooves formed in said surface and extending from said channel to spaced points along the inner longitudinal margin of said cavity, said

cavity, said grooves and said channel forming with said screen member passageways for steam, and means for providing steam to said channel.

4. In a conditioner for open containers of foaming liquids initially having large bubbles, a chest positioned above the path of travel of said containers, said chest having a screen member perforated in a zone beneath which said containers pass, a body member sealed against said screen member, said body member being formed with a cavity in its surface facing said screen member and overlying the perforate zone of said screen member, a channel cut into said body member and a plurality of grooves leading from said channel to said cavity, said cavity, said grooves and said channel forming with said screen member passageways for steam, said screen member having a hole in a zone beneath which said containers pass, an additional groove in said body member providing communication for discharge of steam through said hole, said groove extending through a raised portion extending into said cavity, first means for providing steam to said channel and second means for providing steam to said additional groove.

5. In a conditioner for open containers of foaming liquids initially having large bubbles, a thin chest positioned above the path of travel of said containers comprising, a screen member perforated in a zone beneath which said containers pass and a superposed body member, each of said members having surfaces sealed together around marginal edges, one of said surfaces being formed with a cavity overlying the perforated zone of said screen member, a channel in one of said surfaces and extending along one longitudinal edge thereof and a plurality of spaced, lateral grooves formed in one of said surfaces leading from said channel to said cavity and forming a passageway for steam, and means for providing steam to said channel.

6. In a conditioner for open containers of foaming liquids initially having large bubbles, a thin chest positioned above the path of travel of said containers comprising, a screen member perforated in a zone beneath which said containers pass and a superposed body member, each of said members having surfaces sealed together around marginal edges, one of said surfaces being formed with a cavity overlying the perforated zone of said screen member, a channel and a plurality of grooves leading from said channel to said cavity and forming a passageway for steam, means for providing steam to said channel, said screen member being provided with a steam jet hole, one of said surfaces being provided with an additional groove providing communication for discharge of steam through said hole, and second means for providing steam to said additional groove.
